Primary Examiner — Paula Allen Greene

(74) Attorney, Agent, or Firm — Hamre, Schumann,
Mueller & Larson, P.C.(57) **CLAIM**

The ornamental design for a wireless headphone, as shown and described.

DESCRIPTION

FIG. 1 is a perspective view of the wireless headphone;
 FIG. 2 is a front view of FIG. 1 thereof;
 FIG. 3 is a back view of FIG. 1 thereof;
 FIG. 4 is a left view of FIG. 1 thereof;
 FIG. 5 is a right view of FIG. 1 thereof;
 FIG. 6 is a top view of FIG. 1 thereof; and,
 FIG. 7 is a bottom view of FIG. 1 thereof.
